FIG. 5

FIG. 1 is an end elevational view of a tire showing our new design;

FIG. 2 is a side elevational view thereof;

FIG. 3 is a perspective view thereof;

FIG. 4 is an enlarged, fragmentary plan view of the tread pattern; and

FIG. 5 is a further enlarged fragmentary developed plan view of the tread and side wall pattern.

The tread pattern shown in FIGS. 4 and 5 is repeated throughout the circumference of the tire, while the side opposite to that shown in FIG. 2 is substantially a mirror image thereof.

We claim:

The ornamental design for a tire, as shown and described.
